UNITED STATES PATENT OFFICE.

MAX KOSSMANN, OF BROOKLYN, NEW YORK.

LAMP-SHADE HOLDER.

1,282,593.

Specification of Letters Patent.

Patented Oct. 22, 1918.

Application filed February 18, 1918. Serial No. 217,884.

To all whom it may concern:

Be it known that I, MAX KOSSMANN, a citizen of the United States of America, residing at Brooklyn, Kings county, State of New York, have invented certain new and useful Improvements in Lamp-Shade Holders, of which the following is a full, clear, and exact description.

This invention relates to improvements in lamp-shade holders, the object being to provide a device by means of which a shade can be directly attached to a lamp-bulb. One of the objects of my invention is to produce a device as above mentioned that can be cheaply manufactured and readily manipulated for adjustment in various positions. To accomplish this result, I have designed a holder or bracket, in combination with a lamp shade, that will obviate the necessity of rivets, bolts or the like to connect the holder to the shade. The shade and holder which constitute my invention are closely associated and depend one upon the other for operation; in other words, the shade and holder are constructed to interlock and hence rivets or the like are not needed. Consequently a certain amount of hand labor is dispensed with, which naturally results in a saving.

I will now proceed to describe my invention in detail, the novel features of which I will point out in the appended claim, reference being had to the accompanying drawing, forming part hereof, wherein:

Figure 1 is a sectional view of my improvement illustrated as applied to a lamp bulb;

Fig. 2 is an end view of the shade and holder;

Fig. 3 is a perspective view of the holder;

Fig. 4 is an enlarged fragmentary sectional view, the section being taken on a line 4-4 in Fig. 2; and

Fig. 5 is a perspective view of a modified form of holder, arranged to engage a fabric-shade having a stiffened edge.

My improvement comprises a shade 6 and a holder or frame 7 arranged for detachable and adjustable securing to a light-bulb 8.

As has been stated, I do not employ any rivets, bolts or the like to connect the shade 6 and holder or frame 7, but connect same by detachably interlocking the two together.

As can be seen in Figs. 1 and 4, the shade 6 is provided with an annular peripheral recess or channel 9 which is adapted to receive

the ends of the frame 7. The holder 7 consists of a frame formed of wire connected at the ends 10 and 11, in this instance by a sleeve 12, Fig. 3. Intermediate its ends 13 and 14, the frame 7 is looped as at 15 and 16 to form arms to engage the bulb 8. The frame 7 comprises two parallel side-members 17 and 18, said side-members including the loops 15 and 16, respectively, which form the arms above referred to, said arms being yieldable transversely of the frame. The end-bars or members 13 and 14 connect the side-members 17 and 18 at their ends. As has been stated, the shade 6 and frame 7 are connected by the interlocking action of the annular channel 9 and end-members or bars 13 and 14 when said ends or bars are engaged by said channel. The end members or bars 13 and 14 will be sprung into said annular recess or channel, as is apparent. While the nature of the engagement of the shade and frame is such that premature separation of the shade and frame or holder is prevented, a rotation of the frame or holder, at a right angle to the axis of the shade, is possible. In other words, the shade 6 and frame or holder 7 are rotatably connected; hence the shade 6 can be rotated about its axis while the frame or holder 6 engages a bulb.

As is evident from an inspection of Figs. 1 and 2, the bulb 8 is held between the yieldable arms 15 and 16 of the frame 7. The nature of the connection, between the bulb 8 and yieldable arms 15 and 16, is such that a universal movement of the frame can be obtained, thereby permitting the shade to be adjusted to any desired angular position.

It will be evident from the foregoing description that the connection between the shade and frame is effected without recourse to any bolts, rivets or solder. While the connection permits movement of the shade and holder one upon the other, premature separation of the shade and holder is prevented.

In the form illustrated in Fig. 5, the ends of the frame, instead of being approximately straight, are formed into hooks 19 and 20 to form recesses 21 to receive the stiffened edge of a silk shade, for instance, the stiffening of said edge being usually accomplished by the securing thereto of a wire ring.

What I claim as my invention is:

In combination, a globe having an annular groove formed therein, a wire frame doubled upon itself so as to provide a pair of leg members, and an arcuate loop there-

between, an integral substantially-semi-cylindrical offset formed upon each leg member between its ends, rearwardly thereof, the loop portions of said offsets projecting laterally of said leg members in confronting relation, the free ends of said leg members being bent inwardly thereof at right angles, so as to provide a slit loop portion, a tubular member in which the slit loop portion is

incased, both of said loop portions projecting into the annular groove of said globe so as to support the latter.

Signed at New York city, N. Y., this 15 day of February, 1918.

MAX KOSSMANN.

Witnesses:

EDWARD A. JARVIS,
MAURICE BLOCK.
